UNITED STATES PATENT OFFICE.

WALTER CLARK, OF NEW YORK, N. Y.

PHOTOGRAPHIC CAMERA.

SPECIFICATION forming part of Letters Patent No. 314,317, dated March 24, 1884.

Application filed Augu 15, 1884. (No model.).

To all whom it may concern:

Be it known that I, WALTER CLARK, of the city, county, and State of New York, have invented certain new and useful Improvements 5 in Photographer Cameras, of which the following is a full, clear, and exact description.

My invention relates to cameras having separate apertures for exposure and focusing and fixed object-glasses separate from the plate-holders, whereby the removal and replacing of 10 the plate-holder is not necessary in order to obtain a focus.

It consists in a rotating lens holder which is combined with a camera-box of the construction named, as hereinafter described and 15 claimed.

Reference is to be had to the accompanying drawings, forming a part of this specification, in which similar letters of reference indicate 20 corresponding parts in all the figures.

Figure 1 is a vertical section of the improved camera on the objective plane. Fig. 2 is a cross-section of the camera. Fig. 3 is a side elevation, and Fig. 4 is a horizontal section. 25 Fig. 5 is a section similar to Fig. 1, and Fig. 6 is a horizontal section showing a shutter applied to the box.

A is the box provided with a partition, *a*, that forms a lens and focusing-chamber at the 30 front end of the box, separate from the back space.

In the hinged front of the box is an aperture, *b*, and coincident therewith in partition *a* is an opening, *c*, both openings *b c* being in 35 line with the rear opening that is covered by plate-holder *B*.

In the bottom of the lens-chamber is an opening, *d*, and at the top is the object-glass *e*, fitted over an opening in the box.

40 D is the lens-holder, preferably a solid cylinder bored transversely to receive the lens-tube *f*. The holder is supported by a divided shaft, *g g'*, the inner end, *g'*, of which is sustained by a stand, *h*, while the longer end *g* of 45 the shaft extends through the side of box *A*, and is provided with a wheel, *i*, for turning the shaft and holder. The portion *g* of the shaft is tubular, and through it passes a shaft, *k*, that carries on its end within holder *D* a pinion, *l*, which engages a rack on tube *f*, whereby the tube can be moved in the holder, 50

and the lens thus adjusted to obtain a focus. The position of holder *D* in the chamber is between the apertures *b c*, and also between the aperture *d* and glass *e*, so that by a quarter-turn the opening through the holder can be brought into position for either focusing or exposure. The partition *a* is shaped at the sides of aperture *b* to receive or lap upon the side of the holder, as shown in Fig. 1, and, as 55 shown in Fig. 6, there are also flanges on the partition taking over the ends of the holder. That construction is to exclude light entirely from the aperture *b*, except what passes through the lens. 60

On the end *g'* of the shaft is a spiral spring, *q*, connected at its end to the stand *h* and the shaft, so that it tends to turn the holder *D* in the direction to bring the lens to the aperture *c*. 65

On the outside of the box is a trigger, *r*, 70 which engages a notch in wheel *i*, for retaining the holder with the lens to the aperture *d*.

In order to balance the holder *D* it is fitted with a sliding weight, *s'*, having teeth engaged by the pinion *l*, so that as the pinion moves 75 the lens-tube in one direction the weight *s'* is projected in the opposite direction.

At the bottom of the box *A* is a mirror, *m*, pivoted at one end between flanges *n* by pivots that enter grooves *o* in the flanges, so that the 80 mirror can be shut up closely, and when opened can be drawn forward beneath aperture *d*. The mirror is connected to side arms, *p*, attached to the front of the box, for supporting the mirror at an angle of forty-five degrees. 85 These arms fold up with the mirror.

To obtain a focus, the mirror is let down, the lens-holder turned to bring its aperture in line with aperture *d* and glass *e*, and the lens-tube then adjusted until the object is properly 90 focused on the glass. The trigger *r* is then raised to release the holder, and the spring instantly acts to bring the holder in line with apertures *b c*, and the image is thrown on the plate in holder *B*. 95

At *t* is shown a shutter of usual construction for instantaneous work. This is to be released after the lens-holder is set for exposure, or the shutter may be released by the holder.

In Figs. 5 and 6, a shutter, *t*, is shown as applied between the lens-holder *D* and partition *a*, and hung by arms *u* on the shaft *g g'*. 100

On the shaft is a spiral spring, *w*, connected to rotate the shutter, and the latter is held up over the aperture *c* by a spring-catch, *s*. When the holder *D* is turned to position for taking a picture, its projection *s'* releases catch *s*, and the shutter flies around until it covers the aperture *b*, thus opening the apertures for a moment. The shutter is brought back by a pin, *r*, on the holder, when the latter is turned again.

Having thus described my invention, I claim and desire to secure by Letters Patent—

1. In a camera provided with a separate focusing-chamber, a lens-holder of cylindrical form fitted to rotate so as to bring its aperture in line with either the object-glass or the exposure-apertures, substantially as described.

2. In a photographic camera having a partition forming a separate focusing-chamber, a lens-holder fitted closely in an aperture in the partition, so as to exclude light, and arranged to rotate in its seat, substantially as described.

3. The rotating holder *D*, tube *f*, shaft *gg'*,

shaft *k*, and pinion *l*, combined with box *A* 25 and partition *a*, substantially as described.

4. The lens-holder *D*, shaft *gg'*, spring *q*, and trigger *r*, combined with camera-box *A*, substantially as described.

5. The combination of cylindrical lens-holder *D* and box *A*, having partitions *a*, formed to lap upon the ends and side of the holder, substantially as described.

6. In combination with a photographic camera, the mirror *m*, hung by pivots entering 35 grooves *o* in flanges on box *A*, substantially as described.

7. The sliding weight *s'*, combined with the lens-tube *f*, holder *D*, and pinion *l*, as and for the purpose specified.

8. The rotary shutter *t*, combined with rotary lens-holder *D*, and box *A* having apertured partition *a*, substantially as described, for operation as specified.

WALTER CLARK.
